UNITED STATES PATENT OFFICE.

LEWIS LEONARD HAMILTON, OF DETROIT, MICHIGAN.

MACHINE FOR FORMING FINISHING-MOLDING.

1,386,107.

Specification of Letters Patent.

Patented Aug. 2, 1921.

Application filed January 12, 1920. Serial No. 350,992.

To all whom it may concern:

Be it known that I, LEWIS L. HAMILTON, a citizen of the United States of America, residing at Detroit, in the county of Wayne 5 and State of Michigan, have invented certain new and useful Improvements in Machines for Forming Finishing-Molding, of which the following is a specification, reference being had therein to the accompanying drawings.

The invention relates to the manufacture of finishing molding, such as is used in the manufacture of automobile bodies and for similar purposes, and of that type comprising a filled shell having securing nails projecting from the filling. It is the object of the invention to obtain a machine for the manufacture of such molding, which will automatically set the nails or securing devices in the molten metal forming the filling, and will hold said nails properly positioned until the metal has solidified. To this end, the invention consists in the construction as hereinafter set forth.

25 In the drawings:

Figure 1 is a sectional side elevation of the machine;

Fig. 2 is a cross-section on line 2—2 of Fig. 1;

30 Figs. 3 and 4 are cross-sections, respectively, on lines 3—3 and 4—4 of Fig. 1.

While my invention relates particularly to the incorporation of the securing nails into the molding, this feature is combined 35 with mechanism for manufacturing the complete molding and which is preferably of the following construction:

A are forming rolls arranged in series and adapted to progressively fashion a flat metallic strip B of brass, or other suitable material, into a segmental or trough-shaped form. C is a tension plate for the strip in advance of the forming and feeding rolls A. D is a receptacle for molten metal having a 40 discharge spout E which directs the metal into the trough of the molding, the flow being regulated by an adjustable valve F. G is a gas burner, or other heater, for the receptacle D. H is a fluxing device for applying a suitable flux to the inner face of the molding in advance of the filling.

To secure the nails, or other fastening devices, in the molding it is necessary to press the same into the molten metal in the trough 45 and to hold them in proper position until the metal has solidified. Inasmuch as the

filling metal is usually of a greater specific gravity than the nails, force is required to hold them immersed and to prevent flotation. I have, therefore, devised an effective 60 means for accomplishing this purpose, which consists in electro-magnetically drawing the nails into the molten metal and also holding them, properly positioned, while the metal solidifies. As shown, I is a bar of magnetic 65 metal arranged beneath the molding as it is fed from the fluxing and filling devices. This bar is energized by magnets, J arranged to impart to the bar the same polarity throughout its length. K is a feeding device for successively bringing the nails within range of the magnetic attraction which as shown comprises a wheel having a series of peripheral sockets L therein into which the points of 70 the nails are set. M are spring clips or friction holding devices for retaining the nails in the sockets, and N are releasing pins for the clips M which are operated by a cam or roll O at the point in the revolution of the 75 wheel where the nails come into range of the magnetic attraction. Beyond the nail feeding device K there is arranged a cooling mechanism for which I preferably use a fan P, directing the current of air downward 80 upon the molding and associated devices. The molding is held from displacement during the cooling by a grooved guide roll Q, which bears upon the opposite edges of the shell and provides sufficient clearance for 85 the passage of the nails. R is a brush arranged to remove any of the molten metal which may have accumulated on the outer surface of the molding.

With the construction as described, the operation is as follows: The sheet metal strip B is passed through the tension device C and the forming rolls A by which it is fashioned into the curved or trough-shaped form. It is then fed by the fluxing device H, which 95 coats the inner surface thereof and then to the filling device, where the molten metal from the receptacle B is fed through the spout E. This will completely fill the trough, which is then fed forward beneath 100 the nail feed K. The nails are placed in the feeding device K either by hand or any suitable mechanism, and are successively fed around with the wheel, which is timed with the advance of the molding. Upon reaching 105 the point where the releasing roll O is located, the nails are in substantially vertical

position and as they are under a magnetic influence, they will be drawn downward through the molten metal and into contact with the inner face of the shell. The magnetic attraction is strongest at the center of the arc constituting the cross section of the shell, and therefore, the magnetic pull will tend to hold the nails in upright position. This force will continue to be exerted while the molding is advanced beyond the feeding device K and beneath the cooling device P. Here the metal will be solidified and after fully set, the molding passes out from the range of magnetic attraction, is wiped from any surplus metal by the brush R and is fed out from the machine.

What I claim as my invention is:

1. The combination with means for advancing a hollow strip filled with molten material, of means for feeding securing devices adjacent to said filled strip, and magnetic means for drawing said securing devices into the molten metal and for holding the same properly positioned until the metal solidifies.

2. The combination with means for advancing a molten metal filled strip, of magnetic means for drawing securing devices into the molten metal and retaining the same until the metal is solidified.

3. The method of forming finishing strips comprising filling the hollow strip with molten metal, placing said filled strip in a magnetic field and placing the securing devices within the influence of said magnetic field to draw the same into the molten metal and to retain them in this position until the metal is solidified.

4. The combination with means for forming a metal strip into a trough-shaped section, of means for filling the formed strip with molten metal, means for creating a magnetic field in the path of the advancing filled strip such as to exert magnetic attraction vertically downward of the filled strip, and means for feeding securing devices of magnetic material into the influence of said field, whereby they are drawn into the molten metal and held in upright position thereon until the metal solidifies.

5. The combination with means for filling a trough-shaped metal strip with mol-

ten metal, of means for creating a magnetic field in the path of said strip such as to exert magnetic attraction vertically downward of the molten metal filled strip, means for feeding securing devices of magnetic material into the range of magnetic attraction, whereby said devices are drawn downward through the molten metal and held in upright position therein, and cooling means for solidifying the metal while still in the range of magnetic attraction.

6. The combination with means for advancing a metallic strip, of forming devices for fashioning said strip into a trough-shaped section, means for filling the advancing strip with molten metal, magnetic means including a bar of one polarity extending longitudinally of the advancing strip beneath the same, means for feeding securing devices above the advancing strip and releasing the same when under the influence of magnetic attraction, and cooling means for solidifying the molten metal while said securing devices are held relatively fixed to the advancing strip.

7. The combination with means for advancing a sheet metal strip, of forming means operating upon the advancing strip to fashion the same into a trough-shaped section, means for filling the strip with molten metal, a magnetic device including a longitudinally extending bar of the same polarity arranged beneath the advancing strip, and means for feeding securing devices of magnetic material above said strip, means for successively releasing said securing devices when vertically above the strip and under the influence of magnetic attraction, means for cooling the strip to solidify the metal while still under the influence of magnetic attraction, and means for removing any of the molten metal adhering to the outer face of the strip.

8. The combination with means for advancing a hollow strip filled with molten material, of means for periodically feeding securing devices into said filled strip, and means for retaining said securing devices upright and in spaced relation with each other until the molten metal solidifies.

In testimony whereof I affix my signature.
LEWIS LEONARD HAMILTON.
